FORK OR SIMILAR ARTICLE

Fred O. Forsman, Los Angeles, Calif., assignor to Westland Plastics, Inc., Los Angeles, Calif., a corporation of California

Application June 9, 1958, Serial No. 51,243

Term of patent 14 years

(Cl. D44—29)

Fig. 1 is a front elevational view showing my new design for a fork;

Fig. 2 is a side elevational view of said fork;

Fig. 3 is a rear elevational view of said fork; and

Fig. 4 is a side elevational view of said fork.

The dominant features of my design are shown in full lines.

I claim:

The ornamental design for a fork or similar article, as shown and described.
